Atty.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,300,574.

Specification of Letters Patent. Patented Apr. 15, 1919.

Application filed July 1, 1918. Serial No. 242,697.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Separable Fasteners, (B,) of which the following description, in connection with the accompanying drawings, is a specification, like characters on the drawings representing like parts.

This invention pertains to improvements in separable fasteners, and more particularly, though not exclusively, to fasteners in which a stud enters a socket and is separable therefrom by relative tipping movement of stud and socket in one direction only.

20 In the drawings, which show a preferred form of one embodiment of my invention:

Figure 1 is a front elevation of a preferred form of socket having the stud entered therein;

25 Fig. 2 is a section on the line 2—2 of Fig. 1; and

Fig. 3 is a section on the line 3—3 of Fig. 2.

In the preferred form of my invention selected for illustrative purposes, I have shown a stud 4 having a head 5 presenting a neck 6 and a relatively abrupt shoulder 7. Operating with the stud 4 I provide a socket, which preferably includes a front plate 8, 30 and a rear plate 9, engaging between them a resilient jaw 10 below the stud 4. The front plate 8 of the socket may be died inwardly at 11 to engage behind the shoulder 7 of the stud.

40 The socket may be secured to a curtain 12 in any suitable way, typified by the prongs 13 passing through a clench-plate 14 in the usual manner. Similarly, the stud may be secured to the curtain 15 by prongs 16 passing through the clench-plate 17 in the usual manner.

When the stud is being entered in the socket, the yielding jaw 10 springs downwardly until the fixed jaw 11 enters in the 45 neck 6 of the stud and the yielding jaw 10 also enters in said neck.

The stud and socket cannot be separated

by a direct outward pull because the fixed jaw 11 engages the shoulder 7. The stud and socket cannot be separated by a tipping 55 movement laterally because the openings in the plates 9 or 14 will not permit sufficient latitude of movement, and for much the same reason the stud and socket cannot be separated by an outward pull on the upper 60 side of the socket because the said plates of the casing oppose tipping movement in this direction.

When, however, the lower portion of the socket is pulled outwardly, the shoulder 7 65 will ride over and push downwardly the yielding jaw 10 because the depth of the shoulder is so proportioned that the rounded surface only of the yielding jaw will be engaged by it. Pressure on this rounded 70 surface will cause the yielding jaw to yield downwardly until the jaw is entirely disengaged from the neck 6, at which time sufficient tipping movement has taken place 75 so that the engagement of the shoulder by the fixed jaw 11 will no longer be positive.

While I have shown and described a preferred form of one embodiment of my invention, it will be understood that major changes involving omission, substitution, alteration and reversal of parts, and even changes in the mode of operation, may be made without departing from the scope of my invention, which is best defined in the 80 following claims.

Claims:

1. A stud and socket fastener comprising, in combination, a stud having a head and a neck with an abrupt shoulder between them, a socket having a resilient jaw round in cross section for engagement with said neck behind said shoulder, said neck being relatively shallow, whereby the edge of the head adjacent the shoulder will engage an inwardly sloping rounded portion of the resilient jaw.

2. A stud and socket fastener comprising, in combination, a stud having a head and a relatively shallow neck, with an abrupt shoulder between said head and neck, and a socket having an unyielding jaw for engagement behind said neck at one side thereof and a resilient jaw for engagement with said neck at the opposite side thereof, said

shoulder engaging less than one-half of the diameter of said resilient jaw.

3. A stud and socket fastener comprising, in combination, a stud having a neck and an abrupt shoulder, a socket having a front plate and a back plate, a rigid jaw projecting rearwardly from said front plate and

engaging said neck at one side thereof, and a yielding jaw between said plates engaging the opposite side of said neck.

In testimony whereof, I have signed my name to this specification.

FRED S. CARR.
